UNITED STATES PATENT OFFICE.

NATHAN WILKINSON, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

RHEOSTAT.

1,086,109.

Specification of Letters Patent. Patented Feb. 3, 1914.

Application filed April 17, 1912. Serial No. 691,407.

To all whom it may concern:

Be it known that I, NATHAN WILKINSON, a citizen of the United States, residing at Milwaukee, in the county of Milwaukee and State of Wisconsin, have invented certain new and useful Improvements in Rheostats, of which the following is a full, clear, and exact specification.

This invention relates to rheostats, and 10 more particularly to water rheostats.

Water rheostats have been made wherein the electrodes are both movable and stationary and the effective resistance in the first type is varied by raising and lowering said 15 movable electrodes out of and into water while in the latter type the resistance is changed by varying the height or amount of water with respect to such electrodes. In other words, with respect to stationary electrode 20 type of water rheostats, the effective resistance of such rheostats is varied by causing more or less of the electrodes to be immersed by raising and lowering the level of the water. Such rheostats are being employed 25 more and more for starting motors, such as induction motors. In starting such motors, and motors of various types, comparatively little time is required to accelerate the motors from a position of rest to 30 full speed. Often times it is necessary that the original effective resistance be fairly high. In order to reduce this high resistance within a comparatively short time, a pump of comparatively high capacity will 35 be necessary to pump the water. A motor of corresponding capacity will be necessary to operate the pump. The cost of such an equipment in many instances is quite high.

It is therefore the object of my invention 40 to provide a simple and compact water rheostat adapted to meet all of the requirements of commercial operation, and one which can be operated at a minimum cost. This object is accomplished by providing a 45 water rheostat wherein the electrodes are stationary and are located in water at all times, the effective resistance of such rheostat being varied by raising and lowering an insulated or insulating member or members 50 which are interposed between or surround such electrodes.

The various novel features of my invention 55 will be apparent from the drawings and the description, and will be particularly set forth in the appended claims.

The invention is illustrated in the accompanying sheets of drawings, in which—

Figure 1 is a vertical sectional view of my water rheostat; Fig. 2 is a sectional view of the same rheostat taken on the line 2—2 60 of Fig. 1, looking in the direction indicated by the arrows; Fig. 3 is a vertical sectional view of a water rheostat which is a modification of the one shown in Figs. 1 and 2; Fig. 4 is a horizontal sectional view of the rheostat shown in Fig. 3, the section being taken on the line 4—4 of Fig. 3, looking in the direction indicated by the arrows; Fig. 5 is a diagram of connections showing the 65 rheostat illustrated in Figs. 1 and 2 as connected in the secondary circuit of an induction motor; and, Fig. 6 is a diagram of connections showing the rheostat illustrated in Figs. 3 and 4 as connected in the secondary circuit of an induction motor. 70

This rheostat includes a receptacle or tank 10 containing a fluid 11, preferably water, the height of which may be seen by observing the indicator 9 secured to the upper part of said receptacle. This receptacle is provided with a cover 12 normally retained closed by any suitable means, such as by a bolt and nut 13, said cover being provided with a central opening 14 through which a rod 15 is guided. Secured to the 85 lower end of the rod 15 is an insulated or insulating frame 16 including a plurality of downwardly projecting members 17 which form baffles, to be referred to herein-after. Also extending through the cover 12 90 are conductors 18, to the lower ends of which are secured conducting plates 19, and connected to these conducting plates 19 are groups of electrodes 20, 21, and 22. The conductors 18 also pass through the frame 95 16, being insulated therefrom and insulated from the cover 12 by bushings 23 having collar portions 24 which hold said bushings in a fixed position relative to the cover 12. The conductors 18 are provided with collars 25 to hold said electrodes in a fixed 100 position in the receptacle 12. These electrodes are suspended from the cover 12 by the conductors 18, there being four such conductors in this particular case, one conductor leading to each of the groups 20 and 22 of the electrodes and the other two leading to the electrodes 21. From an electrical standpoint, one conductor 18 would 105 be sufficient for the central group 21 of elec- 110

trodes, but two are used in this particular case primarily to mechanically balance said middle group 21 of electrodes, the rod 15 being located between said two conductors. An 5 electrical balance is, however, obtained by providing the middle group of electrodes with two conductors, and in some cases this may be desirable. Each of the groups of electrodes is provided with electrodes of different lengths for the purpose of making 10 the value of effective resistance more marked under different conditions. These electrodes are interposed between the baffles 17, or groups of electrodes and the baffles are spaced 15 alternately with respect to each other.

The baffles as a unit may be raised and lowered relatively to the electrodes by any suitable means. In this particular case, for 20 the sake of illustration, I have shown fluid pressure means for effecting the desired result. Secured to the rod 15 is a piston 27 which is adapted to be actuated in a cylinder 28. In the position shown the piston and baffle plates are in their lowest positions. The piston may be forced to the 25 upper end of the cylinder by rotating the handle 29 in a counter-clockwise direction until the valve opening 30 registers with the openings 31 of the supply and connecting pipes 32 and 33 respectively. In such 30 position, fluid under pressure passes from pipe 32 through the valve 30^a, pipe 33, and under the piston, gradually raising it and the baffle plates to the desired position. The 35 baffle plates and the piston may be lowered due to the weight of said part by rotating the handle 29 in a clockwise direction until the valve openings 30 and 34 register respectively with the openings 35 and 31 of 40 the exhaust pipe 35^a and connecting pipe 33. By means of this valve and similar arrangements the rheostat may be controlled from a remote point.

As shown, the rheostat is in full resistance 45 position and if connected in circuit with a motor for accelerating or regulating purposes current would pass between the central group of electrodes 21 and the electrodes 20 and 22 respectively and current 50 would pass between electrodes 20 and 22 through the tank 10 and through the water between said tank and said electrodes 20 and 22. In this position the current passing between electrodes develops heat at the bottom 55 of the baffle plates and electrodes. Therefore the water at the bottom portion of the baffle plates and electrodes becomes heated and rises between the baffle plates, escaping upwardly through the frame 16, 60 coming into contact with the cooling coil 37 having an inlet 38 and outlet 39. Cold water is preferably circulated through this cooling coil 37 which may be supported in the tank 11 by brackets 40 having pins 41 65 for separating the adjacent turns of the

coil. As the heated water at the bottom of the baffle plates rises, cold water rushes into its place. A natural circulation is thereby provided, maintaining the water in the rheostat at the desired temperature. It is 70 to be noted that the electrodes are located near the bottom of the tank, the tops of the electrodes being below the middle of the tank. These electrodes are immersed in a comparatively large volume of water. As 75 above mentioned, the water is heated near the bottom of the electrodes and baffles and thereupon rises to the top of the tank and out of contact with any parts of the electrodes. In fact such heated water becomes 80 far removed from such electrodes. This means that cold water is being continuously circulated to those parts of the electrodes from which heat is being conducted. In this way the water is kept at the lowest possible 85 temperature.

In order to decrease the effective resistance of the rheostat, the baffle plates are raised as unit by the fluid pressure means above referred to. These baffle plates may 90 be gradually raised until the lower ends of said baffle plates are raised beyond the upper portions of the electrodes. In this position minimum resistance is offered to the current 95 passing from electrode to electrode. When it is desired to cut in resistance the baffle plates can be lowered by their own weight by moving the handle 29 to the proper position to permit the fluid under the piston 27 to exhaust. These baffle plates are prefer- 100 ably somewhat wider than the electrodes, as shown in Fig. 2, to increase the path of current which may pass around the baffles between the various groups of electrodes, especially when the rheostat is in full re- 105 sistance position. The receptacle 10 is provided with an inlet 44 and an outlet 45 so that a fresh supply of water may be easily provided at any time.

Instead of having the electrodes in the 110 form of plain plates, as shown in Figs. 1 and 2, the electrodes may take the form of conducting cylinders 46, 47, and 48, as shown in the modification in Fig. 3. In this modification the baffles, which may be made 115 of tile or any other insulating material, are also shown in cylindrical form, the various baffles 49, 50, and 51 completely surrounding the groups 48, 47, and 46 of electrodes. For mechanical purposes, each of the groups 120 46, 47, and 48 of cylindrical electrodes is suspended from the cover 52 by two diamet- 125 rically opposite conductors 53, 53^a and 53^b, respectively, as shown diagrammatically in Fig. 6. An electrical balance is also ob- tained in this way. In this instance the longest of the central group of electrodes is directly electrically connected to the tank 54, as shown in Fig. 3, so that current be- 130 tween the central group of electrodes 48

and outer group 46 may be conveyed more directly from one to the other. The effective resistance of this rheostat is varied in precisely the same manner as described in connection with Figs. 1 and 2. These electrodes are arranged concentrically with respect to each other; the baffles are arranged concentrically relatively to each other; and the electrodes and baffles are arranged alternately relatively to each other.

As shown, the rheostat is adapted to be connected in the secondary circuit of an induction motor of the wound rotor type. Its use, however, is not limited to this particular application, but such rheostat may be used with different types of apparatus for various purposes.

There may be various modifications and arrangements other than those here shown and described, and it is my intention to cover all such modifications and arrangements which do not depart from the spirit and scope of my invention, as set forth in the appended claims.

25 What I claim as new is:

1. In a rheostat, the combination of a receptacle containing a fluid, stationary electrodes in said fluid, and movable baffles interposed between said electrodes and displacing only their own volume of liquid for varying the effective resistance of said rheostat.

2. In a rheostat, the combination of a receptacle containing a fluid, stationary electrodes in said fluid, and movable baffles permitting free circulation of fluid therebetween and interposed between said electrodes for varying the effective resistance of said rheostat.

40 3. In a rheostat, the combination of a receptacle containing a fluid, groups of stationary electrodes of different lengths within said receptacle, and movable means interposed between said groups of electrodes for varying the effective resistance of said rheostat.

45 4. In a rheostat, a receptacle having a cover and containing a liquid, stationary electrodes suspended from said cover and immersed in said liquid, and movable barriers separating said electrodes for varying the effective resistance of said rheostat, said barriers being openly connected as a unit to permit their free movement in said liquid.

50 5. In a rheostat, the combination of a receptacle containing a liquid, stationary electrodes supported in said receptacle, and movable baffles interposed between said electrodes and being freely movable in said liquid as a unit for varying the effective resistance of said rheostat.

55 6. In a rheostat, the combination of a liquid containing tank, groups of electrodes within said tank, the electrodes of each group varying in length, and movable means

including a plurality of baffles movable as a unit to vary the effective resistance of said rheostat.

7. In a rheostat, the combination of a receptacle containing a liquid, stationary electrodes in said liquid, and movable means surrounding said electrodes and displacing only its own volume of liquid for varying the effective resistance of said rheostat.

75 8. In a rheostat, the combination of a tank containing a liquid, stationary electrodes in said liquid, and a member surrounding one of said electrodes adapted to be moved relatively thereto for varying the effective resistance of said rheostat and to displace only its own volume of liquid in its movement.

80 9. In a rheostat, the combination of a receptacle containing a liquid, stationary electrodes immersed in said liquid, and movable baffles interposed between said electrodes and between some of said electrodes and said receptacle for varying the effective resistance of the rheostat, said baffles being freely movable in and displacing only their own volume of said liquid.

90 10. In a rheostat, the combination of a tank containing a liquid, cylindrical electrodes in said liquid, and a member movable with respect to said cylindrical electrodes for varying the effective resistance of said rheostat without substantially changing the level of said liquid.

100 11. In a rheostat, the combination of a receptacle containing a liquid, a plurality of stationary cylindrical electrodes in said liquid, and a cylindrical non-conducting member having an opening in each end and movable with respect to said electrode for varying the effective resistance of the rheostat.

105 12. In a rheostat, the combination of a liquid containing tank, groups of stationary spaced and connected cylindrical electrodes, and a plurality of movable non-conducting cylindrical members interposed between said groups of electrodes and being movable as a unit for varying the effective resistance of said rheostat.

110 13. In a rheostat, the combination of a liquid containing tank, groups of stationary spaced and connected cylindrical electrodes, a plurality of movable non-conducting cylindrical members interposed between said groups of electrodes and being movable as a unit for varying the effective resistance of said rheostat.

115 14. In a rheostat, the combination of a receptacle containing a liquid, stationary electrodes in said liquid, one of said electrodes being in contact with said tank, and movable means interposed between and surrounding said stationary electrodes for varying the effective resistance of said rheostat.

120 15. In a rheostat, the combination of a

- fluid containing receptacle, a stationary electrode in said receptacle, and a movable member arranged concentrically with respect to said electrode and having an opening in each end for varying the effective resistance of said tank.
16. In a rheostat, the combination of a receptacle containing a liquid, stationary concentrically arranged electrodes in said liquid, and concentrically arranged members freely movable and displacing no more than their own volume of said liquid for varying the effective resistance of said rheostat.
17. In a rheostat, the combination of a tank containing a liquid, stationary concentrically arranged electrodes in said liquid, and movable concentrically arranged members surrounding said electrodes and being arranged alternately with respect to said electrodes for varying the effective resistance of said rheostat without substantially changing the level of said liquid.
18. In a rheostat, the combination of a receptacle containing a liquid, stationary electrodes immersed in said liquid, and a movable baffle for varying the effective resistance of said rheostat, said electrodes being located in the lower half of said receptacle so that liquid heated at or near the electrodes may circulate from said electrodes to a remote part of the receptacle for cooling.
19. In a rheostat, the combination of a receptacle containing a liquid, stationary electrodes immersed in said liquid, a movable baffle for varying the effective resistance of said rheostat, said electrodes being located in the lower half of said receptacle so that liquid heated at or near the electrodes may circulate from said electrodes to a remote part of the receptacle for cooling.
20. In a rheostat, the combination of a fluid containing receptacle, electrodes therein, one of said electrodes having a plurality of conductors connected thereto for electrical balance purposes, and a member movable relatively to said electrodes for varying the effective resistance of said rheostat.
21. The combination in a receptacle containing liquid, of electrodes, a plurality of baffles freely movable as a unit between said electrodes, said baffles and said liquid acting to create a resistance path of variable length between said electrodes, and cooling means in said receptacle adapted to cool and circulate the liquid that has become heated between said electrodes.
22. In a rheostat, a receptacle containing fluid, electrodes, and a baffle adapted to act as a barrier between said electrodes, said baffle and said electrodes being wholly immersed in said fluid in all current carrying positions of said parts.
23. In a rheostat, the combination of a receptacle containing a fluid, electrodes in said receptacle, and baffles interposed between said electrodes, said baffles and said electrodes being relatively movable for varying the effective resistance of said rheostat and permitting free circulation of said fluid between said parts.
